DESIGN FOR A FLUID DISPENSING UNIT

Ralph C. Pierson and Willis G. Schepman,
Indianapolis, Ind.

Application March 16, 1940, Serial No. 90,990

Term of patent 14 years

To all whom it may concern:

Be it known that we, Ralph C. Pierson and Willis G. Schepman, residing at Indianapolis, in the county of Marion and State of Indiana, have invented a new, original, and ornamental Design for a Fluid-Dispensing Unit, of which the following is a specification, reference being had to the accompanying drawing, forming a part thereof.

In the drawing, Figs. 1, 2, and 3 are respectively front elevational, back elevational, and plan views of a fluid-dispensing unit illustrating our design.

We claim:

The ornamental design for a fluid-dispensing unit, substantially as shown.

RALPH C. PIERSON.
WILLIS G. SCHEPMAN.
